(57) **CLAIM**

The ornamental design for a vehicular side step, as shown and described.

DESCRIPTION

FIG. 1 is a perspective view of a vehicular side step showing my new design;

FIG. 2 is a top plan view thereof;

FIG. 3 is a front elevational view thereof;

FIG. 4 is a bottom plan view thereof;

FIG. 5 is a left side view thereof;

FIG. 6 is a right side view thereof; and,

FIG. 7 is a rear elevational view thereof.

The broken lines shown in FIG. 4, illustrate portions of the vehicular side step that form no part of the claimed design.
